UNITED STATES PATENT OFFICE.

JESSE D. DE BERRY, OF SMITHVILLE, MISSOURI.

FOLDING EGG-CASE.

SPECIFICATION forming part of Letters Patent No. 291,699, dated January 8, 1884.

Application filed June 27, 1883. (No model.)

To all whom it may concern:

Be it known that I, JESSE D. DE BERRY, of Smithville, Clay county, Missouri, have invented a new and Improved Folding Egg-Case, 5 of which the following is a full, clear, and exact description.

The object of my invention is to provide a new and improved case for shipping eggs and other articles, which case can be folded very 10 compactly, so as to occupy very little space when not in use and while being returned to the shipper.

The invention consists in a folding egg-case constructed with low side and end pieces fixed 15 to the bottom, side boards hinged to the upper edges of the side pieces, and boards hinged to the ends of the side boards, and partitions hinged to the bottom of the case and to a low partition in the case, whereby the case can be 20 folded very compactly when not in use. The end boards are provided with hasps having slots, through which staples on the side boards can pass.

Reference being had to the accompanying 25 drawings, forming part of this specification, in which similar letters of reference indicate corresponding parts in all the figures, Figure 1 is a plan view of my improved folding egg-case, showing the cover removed. Fig. 2 is an 30 end view of the same, parts being broken out and parts shown in section, the case being folded; and Fig. 3 is a side view of part of the case which is shown folded, parts being broken out and others shown in section.

The case is constructed with low sides and 35 end pieces, A B, nailed to the edges of the bottom C. The height of the side and end pieces is preferably equal to one-fourth of the height of the case. To the upper edges of the side 40 pieces, A, side boards, D, are hinged in such a manner that the said hinged side boards can be folded down toward the interior of the case. To each side board, D, one end board, E, is 45 hinged by hinges F, the two end boards, E, being hinged to the opposite ends of the opposite side boards. On the free end of each end board, E, a hinged hasp, G, is fastened, which is provided at its free end with a slot, a, through which a staple, H, is adapted to 50 pass, which projects from the outer surface

of a side board, D, at the end opposite the one at which the hinge F is fastened. A locking pin or key, J, can be passed through the staple after the said staple has been passed through the end of the hasp. To the upper 55 surface of the bottom C a low central partition, K', extending from side to side, is secured, and to the upper edge of the partition K' a partition, K, is hinged in such a manner that it can be folded down. In each compartment 60 a partition, L, is hinged in such manner that it can be folded down, the said partitions swinging in opposite directions. The partitions K and L are provided with handle-knobs M. The case is provided with a cover, N, having 65 downwardly-projecting flanges, O, at the side edges, and having the upper surface beveled off at the end edges, as at m, to permit the hinges F to fold over the thin beveled edges, when the ends B are folded down over the 70 cover N, as in Figs. 2 and 3. The crates are placed in the four compartments formed by the partitions K L.

When the egg-case is not in use—for instance, when it is being returned to the shipper—the partitions L and K are folded down, 75 the side boards, D, are folded over the partitions L K, the cover N is placed on the sides D, and the end boards, E, are folded over the cover N. Then the end boards, E, are locked 80 in place by means of the hasps G, the staples H, and the keys J.

Having thus described my invention, I claim as new and desire to secure by Letters Patent—

1. A folding egg-case constructed, substantially as herein shown and described, with low side and end pieces secured to the bottom, side boards hinged to the upper edges of the side pieces, and end boards hinged to the ends of the side boards, as set forth. 85

2. A folding egg-case constructed with low side and end pieces secured to the bottom, side boards hinged to the upper edges of the side pieces, end boards hinged to the ends of the side boards, and folding partitions hinged 95 to the bottom of the case, substantially as herein shown and described, and for the purpose set forth.

3. In a folding egg-case, the combination, with the side and end pieces, A B, secured to 100

the bottom C, of the side boards, D, hinged to the upper edges of the side pieces, the end boards, E, hinged to the ends of the side boards, the hinged hasps G, secured to the free 5 ends of the end boards, and the staples H on the side boards, substantially as herein shown and described, and for the purpose set forth.

4. In a folding egg-case, the combination, with the side and end pieces, A B, secured to 10 the bottom C, of the side boards, D, hinged to the upper edges of the side pieces, the end boards, E, hinged to the ends of the side boards, and the cover N, having the upper 15 surface beveled at the end edges, substantially as herein shown and described, and for the purpose set forth.

5. In a folding egg-case, the combination, with side and end pieces, A B, secured to the bottom C, of the side boards, D, hinged to the side pieces, the end boards, E, hinged to 20 the ends of the side boards, the partition K, hinged to the partition K', and extending from side to side, and the partitions L, hinged to the bottom and extending from the ends to the partition K, substantially as herein shown 25 and described, and for the purpose set forth.

JESSE D. DE BERRY.
